UNITED STATES PATENT OFFICE.

EDWARD Z. LEWIS, OF CHICAGO, ILLINOIS, ASSIGNOR TO THE GENERAL MANIFOLD AND PRINTING COMPANY, OF FRANKLIN, PENNSYLVANIA, A CORPORATION OF PENNSYLVANIA.

MANIFOLDING SALESMAN'S CHECK.

1,039,766.

Specification of Letters Patent.

Patented Oct. 1, 1912.

Application filed December 12, 1910. Serial No. 596,923.

To all whom it may concern:

Be it known that I, EDWARD Z. LEWIS, a citizen of the United States, and a resident of Chicago, in the county of Cook and State 5 of Illinois, have invented certain new and useful Improvements in Manifolding Salesmen's Checks; and I do hereby declare that the following is a full, clear, and exact description thereof, reference being had to the 10 accompanying drawings, and to the letters of reference marked thereon, which form a part of this specification.

This invention relates to a manifolding salesman's check and the object of the invention is to provide a check constructed in such a way that it is not only adapted for the production of the usual original and carbon copies of the same, but is also adapted to produce in inscribing the original bill 20 an indestructible record of the bill which cannot be tampered with without detection and upon which will be reproduced whatever is written upon the original bill including any changes or alterations made 25 thereon.

The invention relates to the same kind of salesman's check as that shown and described in Letters Patent No. 972,551, issued to me on October 11th, 1910, and, as 30 shown and described herein, is applied to a check for meal service and more particularly to the checks used on dining cars. In said check form there is provided an original check upon which the order is written, two or more cook's checks underlying said original check, upon which carbon impressions are made of what is written on the bill, and a backer or card to which all of the parts 35 are attached. Means are provided between the original check and the cook's checks to produce carbon impressions on the latter, and after the order is written on the original the carbon copy of the same is torn out and sent to the cook. In case additional 40 orders are written there remains another cook's check or slip which will receive a carbon reproduction of what is added to the bill. After this is detached the total is written on the original which is reproduced 45 on the card.

The invention relates specifically to the construction of the original check.

In the drawings:—Figure 1 shows my 50 improved check with parts torn away or turned up to disclose the underlying sheets.

Fig. 2 is a section through the check on the line 2—2 of Fig. 1. Fig. 3 is a section on the line 3—3 of Fig. 1. Fig. 4 is a perspective view of the original check showing parts torn away. Fig. 5 is a plan view of 60 the sheet containing the original check, before it is folded. Fig. 6 is a perspective view illustrating the manner in which the carbon sheet is interfolded with the sheet containing the original check. Fig. 7 is a perspective view illustrating a modified form of the check. Fig. 8 is a section through the check shown in Fig. 7 on the line 8—8 thereof. Fig. 9 is a section on the line 9—9 of Fig. 7.

Referring now to that embodiment of my 70 invention illustrated in Figs. 1 to 6, inclusive, A is the original check as a whole; B, C, the duplicate checks which are herein referred to as cook's checks; and D, the cardboard backer to which said several 75 checks are attached. As illustrated in the drawings, each of the checks is printed as usual with any desired items and with such other printed matter as is called for by the particular use to which the check is to be 80 put.

The original check A is a composite check and comprises a sheet A¹ containing an original and a record check and an interfolded carbon sheet A². The strip or sheet 85 of paper A¹ (see Fig. 5), in one direction, is equal to the height of the check and in a direction at right angles thereto is equal to twice the width of the check. Said sheet is divided into two sections a¹ a² which are defined by means of a line of perforations or of score marks x to permit the ready folding of one section upon the other. Upon the obverse side of one section, the right hand section a² as shown in the drawings, is printed an original check form A^x, while upon the reverse side of the other section a¹, that is to say upon the side of the sheet A¹ opposite the side upon which the original check form appears, is printed a duplicate 95 copy or record A^x of the original check, as shown in dotted lines in Fig. 5, this form being arranged so that when the section a¹ is folded under the section a², the original check and duplicate check will register with 100 each other.

With the sheet A¹ is interfolded a carbon sheet A² (see Figs. 4 and 6) having a carbon surface on both sides. Said carbon sheet is folded along a longitudinal median 110

line a^3 to form sections a^4 , a^5 , each of which is of substantially the width of the sections a^1 , a^2 of the sheet A^1 and of a length somewhat less than that of said sections a^1 , a^2 . 5 When interfolded with the sheet A^1 , the section a^4 of the carbon sheet A^2 lies between the sections a^1 and a^2 of the sheet A^1 , while the section a^5 of the carbon sheet lies beneath the section a^2 of said sheet A^1 . After 10 being interfolded as described, the sheet A^1 and the carbon sheet A^2 are permanently stitched together along the top and bottom of the printed form A^x as indicated at a^6 , a^7 . The original check A and the two duplicate 15 checks B , C are then secured to the card backer D by means of staples d , d , or in any other convenient manner.

It will be apparent that in the assembled 20 manifolding check the carbon sheet section a^5 , which is on the underside of the original check A , will, in the first instance, come in contact with the uppermost cook's check B and, after said cook's check is detached, 25 in contact with the one next underneath it, C , and that when this is torn out, said carbon section comes in contact with the card or backer D .

As shown herein, the sections a^1 and a^2 of the folded sheet A^1 are provided below 30 the forms A^x , A^y with parts a^8 , a^9 which extend below the carbon sheet sections a^4 , a^5 and upon which are printed punch checks a^{10} , a^{11} printed with items of dollars and cents. The part a^8 containing the punch 35 check a^{10} is made detachable from the composite check A by means of a line of perforations a^{12} , and after the composite check has been punched to indicate the total 40 amount of the bill, this part a^8 is detached and handed to the purchaser as a receipt. The amount punched is indicated on the punch check a^{11} which remains attached to the record check section a^1 .

The advantages of my improved mani- 45 folding salesman's check are apparent from the above description. An unalterable record of whatever is written on the original section is produced on the record check section. It is impossible to get at this record 50 check section to alter or change any item without tearing the check along the stitching lines.

In the check above described the only way 55 that the check might be tampered with would be by inserting a card between the original check section and the record check section which would prevent the items written on the original check section from being duplicated on the record check section. This 60 would be of little moment, however, for the reason that it would also prevent the order from being duplicated on the cook's check. Nevertheless, in order to prevent such a possibility I provide the modification illustrated 65 in Figs. 7 to 9. In this construction the

composite check A^3 is made as before by interfolding a sheet E^1 with a carbon sheet E^2 , and the printing and arrangement of the parts are in every way the same as in the case first described, except that the fold line x^1 of the sheet E^1 is located on the right, and the fold line x^2 of the carbon sheet, on the left. The two sheets are then permanently stitched together by a vertical line of stitching y which connects the top and bottom 70 lines of stitching a^6 , a^7 . This permanently incloses the record sheet on all sides and prevents the insertion of a card to prevent the order written on the original check section from being reproduced on the record check section. By arranging the fold lines of the sheet E^1 and of the carbon sheet E^2 in the manner described, the vertical line of stitching 75 is located on the left so as not to come within the column in which the items of cost 80 of the articles ordered are written.

I claim as my invention:—

1. A manifolding salesman's check comprising, in combination with a suitable backer and one or more detachable duplicate check forms, a composite check consisting of a single piece of paper folded to form an outer original check section and record check section lying beneath said original check section, and a carbon sheet 95 interfolded with said check forming sheet, having one section located between said original and record check sections, and a second section located beneath said record check section, the parts of said composite check including said original and record check sections and said interfolded carbon sheet being permanently stitched together 100 at the top and bottom thereof, and means for securing said checks to said backer. 105

2. A manifolding salesman's check comprising, in combination with a suitable backer and one or more detachable duplicate check forms, a composite check consisting of a single piece of paper folded to form an outer original check section and a record check section lying beneath said original check section, and a carbon sheet interfolded with said check forming sheet, having one section located between said 110 original and record check sections, and a second section located beneath said record check section, the parts of said composite check being permanently stitched together 115 at the top and bottom thereof, and along the side margin formed by the free edges of said sheet. 120

3. A composite record check comprising a sheet of paper folded in two sections, an original check section and a record check 125 section, and a carbon sheet folded in two sections, said sheet of paper and carbon sheet being interfolded with a carbon section between said original and record sections and a carbon section under said record 130

check section, the parts of said composite check being permanently stitched together at the top and bottom thereof.

4. A composite record check comprising a sheet of paper folded in two sections, an original check section and a record check section, and a carbon sheet folded in two sections, said sheet of paper and carbon sheet being interfolded with a carbon section between said original and record sections and a carbon section under said record check section, the parts of said composite check being permanently stitched together at the top and bottom and along the side margin formed by the free edges of said sheet.

5. A manifolding salesman's check comprising, in combination, a suitable backer and one or more detachable duplicate check forms, a composite check consisting of a single piece of paper folded to form an outer original check section and a record

check section lying beneath said original check section, transferring means interposed between said original check section and said record check section, and transferring means interposed between said record check section and said detachable duplicate check forms, said composite check including said original and record check sections and said transferring means being permanently stitched together at the top and bottom and along the side margin formed by the free edges of said folded sheet, and means for securing said several parts to said backer.

In testimony, that I, claim the foregoing as my invention I affix my signature in the presence of two witnesses, this 19th day of November A. D. 1910.

EDWARD Z. LEWIS.
